GOLF BAG STAND

Howard A. Benzel, 28 Lombardy St.,
Lancaster, N.Y. 14086

Filed Mar. 10, 1969, Ser. No. 16,150

Term of patent 14 years

Int. Cl. D21—03

U.S. Cl. D34—5

Fig. 1.

Fig. 2.

Fig. 3.

Fig. 4.

Fig. 5.

Fig. 6.

FIG. 1 is a side elevational view of a golf bag stand, showing my new design;

FIG. 2 is an elevational view of the golf bag stand of FIG. 1, rotated counterclockwise through about ninety degrees;

FIG. 3 is an elevational view showing the side thereof opposite that shown in FIG. 2;

FIG. 4 is an elevational view showing the side thereof opposite that shown in FIG. 1;

FIG. 5 is a top plan view thereof; and

FIG. 6 is a bottom plan view thereof.

I claim:

The ornamental design for a golf bag stand, substantially as shown.
